RING AND TRAVELER FOR SPINNING AND TWISTING FRAMES

Ralph Ragan, Atlanta, Ga., assignor to Steel Heddle Manufacturing Company, Philadelphia, Pa., a corporation of Pennsylvania

Application April 18, 1935, Serial No. 16,954

17 Claims. (Cl. 118—59)

This invention relates to rings and travelers for spinning and twisting frames, and in some respects comprises certain improvements in the invention described and claimed in my previous application for Letters Patent, Serial No. 731,248.

The principal object of the present invention is to provide a ring and traveler for spinning and twisting frames, which will operate more efficiently and uniformly than the rings and travelers at present in common use.

A further object of the invention is to provide a ring and traveler to be used in connection therewith, which are so constructed and arranged as to insure a large bearing surface at the place where the traveler contacts with the ring in its movement about the same.

A further object of the invention is to provide improved means for lubricating the bearing surface of the ring, whereby a sufficient but not excessive quantity of lubricant will at all times be present on said bearing surface.

A further object of the invention is to provide a ring and traveler construction in the use of which there is taken into account the resultant of the forces imposed by the tension of the yarn as well as the centrifugal action of the mass of the traveler, to the end that a more uniform twist in the yarn will be obtained, and irregularities in and breakage of the yarn will be greatly reduced.

A further object of the invention is to provide an improved form of traveler having a bearing portion to which the yarn engaging portion of said traveler is connected in such manner that said yarn engaging portion may readily and automatically assume the proper angular position with respect to the bearing portion, to compensate for variations in the tension of the yarn and in the speed of rotation of the spindle.

The nature and characteristic features of the invention will be more readily understood from the following description, taken in connection with the accompanying drawing forming part hereof, in which:

Figure 1 is a top plan view of a ring and traveler employed in connection therewith, embodying the main features of the present invention;

Fig. 2 is an enlarged sectional view thereof, taken approximately on the line 2—2 of Fig. 1;

Fig. 3 is an elevational view of the traveler shown in Fig. 2, this view being taken in the direction of the arrow 3 on Fig. 2, the traveler shown being that provided where the yarn is to have a right hand twist imparted thereto, and the device is to be used in connection with a spindle

rotating in a contra-clockwise direction, as indicated by the arrow shown in connection with Fig. 3;

Fig. 4 is a horizontal section of the bearing portion of the traveler shown in Fig. 3, this section being taken on the line 4—4 of Fig. 3, the yarn engaging portion of the traveler being shown removed therefrom;

Fig. 5 is a view similar to Fig. 3, but illustrating a form of traveler to be used where the yarn is to have a left hand twist imparted thereto, and the spindle rotates in a clockwise direction, as indicated by the arrow shown in connection with Fig. 5;

Fig. 6 is a similar view of a modified form of traveler, which may be used under certain conditions in which the hole in which the yarn engaging portion is mounted is symmetrically disposed in the bearing portion of the traveler, the yarn engaging portion being in this instance swung in either direction, whereby the same may be used for imparting either a right or a left hand twist to the yarn; and

Fig. 7 is a similar view of another modified form of traveler, in which the bearing portion is provided with a pair of holes, in either of which the yarn engaging portion of the traveler may be mounted, depending upon whether the traveler is used to impart a right or a left hand twist to the yarn.

It will, of course, be understood that the description and drawing herein contained are illustrative merely, and that various modifications and changes may be made in the structure disclosed without departing from the spirit of the invention.

Referring to the drawing, 10 is a ring made of any preferred material, such, for example, as any of the alloy steels commonly used for such purpose. This ring may be hardened and polished in the usual manner. The ring 10 has a base portion 11, of sufficient area in cross-section to afford the necessary rigidity.

A portion 12 extends upwardly from the base portion 11 of the ring, being so shaped as to provide an inner bearing surface 13, which is made frusto-conical for a purpose to be presently explained. The small diameter of the frusto-conical bearing surface 13 is disposed upwardly.

At the upper end of the upwardly extending portion 12 there is provided an inwardly extending flange 14, which serves to limit the upward displacement of the traveler to be hereinafter described. At the lower part of the ring 10 there is provided an inwardly extending flange 15,

which serves to limit the downward displacement of said traveler, and also assists in feeding a lubricating medium to the bearing surface 13 of the ring in an effective manner.

5 An oil reservoir 16, preferably made of pressed sheet metal, is mounted on the ring 10 by means of an upwardly extending rim 17, which frictionally engages the outer surface of the base portion 11 of the ring. The oil reservoir 16 is so shaped as to provide an annular chamber 18, disposed below the base portion 11 of the ring. In this chamber 18 there is mounted an annular wick 19, made of felt or other suitable material, which extends upwardly from the bottom of the 10 annular chamber 18, and has its upper portion chamfered, as at 20, so as to provide a relatively narrow upper edge portion which bears against the under surface of the inwardly extending flange 15 of the ring.

15 The inner wall 21 of the oil reservoir 16 extends upwardly to form a guard to shield the oil covered surfaces of the ring 10 against the accumulation of the fly and grit which are thrown centrifugally outward during the spinning and twisting operation. This guard wall 21 of the oil reservoir also serves to prevent broken ends of the yarn from coming in contact with the oil covered surfaces of the ring and becoming fouled thereby. Furthermore, the guard wall 21 serves 20 to prevent the base of the bobbin from contacting with the traveler, as sometimes happens with the ordinary types of rings and travelers.

25 The traveler comprises two members, a yarn engaging portion 22, made of a length of wire or a metallic strip, suitably bent to provide a curved portion 23 around which the yarn passes in the usual manner; and a bearing portion 24, comprising a small metallic block having one surface 25 complementary in shape to the frusto-conical bearing surface 13 of the ring.

30 The yarn engaging portion 22 of the traveler is preferably made of round wire having its ends bent inwardly toward each other, and the bearing block portion 24 of the traveler is provided with one or more holes 26, in which the inturned end 27 of said yarn engaging portion of the traveler is positioned. The other inturned end 28 of the yarn engaging portion 22 of the traveler serves to prevent the traveler from becoming 35 detached from the ring by reason of the outwardly extending flange 29 provided at the top of the ring, over which the end 28 of the yarn engaging portion 22 of the traveler may be snapped in the usual manner when it is desired to mount or demount the traveler with respect 40 to the ring.

35 The hole 26 in the bearing block portion 24 of the traveler preferably extends entirely through said bearing block. However, the inturned end 27 of the yarn engaging portion of the traveler is preferably shorter than the thickness of the block, in this manner providing a pocket in which a portion of the lubricating medium may be trapped, thereby to be more evenly distributed 45 over the bearing surface 13 of the ring.

40 The hole 26 in the bearing block portion 24 of the traveler must be properly located for the most efficient operation of the traveler, the determination of the location being made by taking 50 into consideration the distribution of the mass of the bearing block portion 24 and of the yarn engaging portion 22 of the traveler, as well as the normal operating speed of the spindle and the tension of the yarn.

45 75 If desired, the end 27 of the yarn engaging

portion 22 of the traveler may be mounted in the bearing block portion 24 of the traveler with a forced fit, the yarn engaging portion being set at the proper angle with respect to the bearing block portion to insure the most efficient operation. However, it may be found preferable to permit the yarn engaging portion 22 of the traveler to have a certain pivotal motion with respect to the bearing block portion 24 thereof, so that in the operation of the device the yarn engaging 10 portion may automatically adjust itself to the proper angular position when changes occur in the speed of rotation of the spindle and in the tension of the yarn.

50 Ordinarily, the best location for the hole 26 in 15 the bearing block portion 24 of the traveler, which is used for the mounting of the yarn engaging portion 22, will be slightly above the horizontal center and to the left of the vertical center of said bearing block portion, as shown in 20 Fig. 3, when the traveler is to be used for imparting a right hand twist to the yarn; and to the right of the vertical center, as shown in Fig. 5, when the traveler is to be used for imparting a left hand twist to the yarn.

25 In some instances it will be found permissible to locate the hole 26 on the vertical center of the bearing block portion 24, as shown in Fig. 6, the angular position assumed by the yarn engaging portion 22 serving to obtain the proper re- 30 action whereby the bearing surface 25 of the bearing block portion 24 of the traveler will be kept in the proper complementary relationship with respect to the frusto-conical bearing surface 13 of the ring 10.

35 In still other instances it may be found desirable to provide two holes 26 in the bearing block portion 24 of the traveler, as shown in Fig. 7, whereby the yarn engaging portion 22 may be alternatively positioned in said holes, accordingly 40 as the traveler is to be used for imparting a right or a left hand twist to the yarn.

45 A ring and traveler constructed as aforesaid will operate in a manner peculiar to itself, and differently from any of the various types of rings and travelers heretofore used or suggested. By reason of the provision of the frusto-conical surface 13 of the ring at the proper angle, the centrifugal action will tend to cause the traveler to descend, the force thus imparted being in addition to the gravitational force. As opposed to this, the tension of the yarn passing around the yarn engaging portion 22 of the traveler will tend 50 to raise the traveler. The desideratum is to obtain a balance between the forces thus imposed 55 on the traveler.

60 It has been found, however, that even where the traveler is provided with a bearing block portion, if the mass thereof be disposed centrally with respect to the yarn engaging portion of the traveler, there will be a tendency on the part of the traveler to cock to an angular position, this by reason of the yarn extending tangentially from the bobbin to the traveler.

65 In the present instance this tendency is overcome by the off-center position of the hole 26, in which the yarn engaging portion 22 of the traveler is mounted, as well as the angular position at which the said yarn engaging portion is fixed, or which it assumes when the same is pivotally mounted with respect to the bearing block portion 24 of the traveler. In this manner there is provided a distribution of the mass of the traveler which serves to correct the tendency of the traveler to cock and bind on the ring.

The provision of the improved means for lubricating the bearing surface 13 of the ring 10 is also an important feature of the present invention. In this instance the oil contained within 5 the annular chamber 18 of the reservoir 16 will be carried upwardly by the capillary action of the wick 19 until it encounters the lower surface of the inwardly extending flange 15 of the ring. The oil will then creep over the inner surface of 10 said flange 15, and pass to the bearing surface of the ring in such quantity as to lubricate said bearing surface sufficiently, yet not to an excessive extent.

A ring and traveler constructed as aforesaid 15 will be found to operate more evenly and uniformly than the rings and travelers at present in common use, and burning of the ends of the traveler, by reason of their frictional engagement with the flanges of the ring, will be eliminated. 20 In fact, the entire structure will be found to operate in a much more satisfactory manner than the present types of rings and travelers, and will permit operation at higher speeds.

I claim:

25 1. A spinning ring having an inner frusto-conical bearing surface adapted to be engaged by a portion of a traveler, said ring also having at the top a flange extending angularly inward from the upper edge portions of said bearing surface to 30 limit the upward displacement of a traveler mounted on the ring, and a flange extending angularly inward from the lower edge portions of said bearing surface to limit the downward displacement of the traveler.

35 2. A spinning ring having an inner frusto-conical bearing surface adapted to be engaged by a portion of a traveler, said ring also having at the top a flange extending angularly inward from the upper edge portions of said bearing surface to 40 limit the upward displacement of a traveler mounted on the ring, a flange at the bottom extending angularly inward from the lower edge portions of said bearing surface to limit the downward displacement of the traveler, and an 45 outwardly extending flange at the top for preventing disengagement of the traveler from the ring.

3. A spinning ring having an inner frusto-conical bearing surface, and a traveler cooperating 50 therewith having a yarn engaging portion and a bearing portion comprising a block provided with an enlarged bearing surface complemental to and engaging the bearing surface of the ring, the yarn engaging portion comprising a curved member 55 extending over the top of the ring and having in-turned ends, and the bearing portion having a hole in which one of the inturned ends of the yarn engaging portion is positioned.

4. A spinning ring having an inner frusto-conical bearing surface, and a traveler cooperating 60 therewith having a yarn engaging portion and a bearing portion comprising a block provided with an enlarged bearing surface complemental to and engaging the bearing surface of the ring, the 65 yarn engaging portion comprising a curved member extending over the top of the ring and having in-turned ends, and the bearing portion having a hole in which one of the inturned ends of the yarn engaging portion is positioned, said 70 hole being located to one side of the vertical center of said bearing portion.

5. A spinning ring having an inner frusto-conical bearing surface, and a traveler cooperating 75 therewith having a yarn engaging portion and a bearing portion comprising a block provided with an enlarged bearing surface complemental to and 80 engaging the bearing surface of the ring, the yarn 85 engaging portion comprising a curved member

an enlarged bearing surface complemental to and 85 engaging the bearing surface of the ring, the yarn 90 engaging portion comprising a curved member extending over the top of the ring and having in-turned ends, and the bearing portion having a 95 hole in which one of the inturned ends of the yarn 100 engaging portion is positioned, said hole being located above the horizontal center and to one side of the vertical center of said bearing portion.

6. A spinning ring having an inner bearing surface, and a traveler cooperating therewith having a yarn engaging portion and a bearing portion comprising a block provided with an enlarged bearing surface complemental to and 15 engaging the bearing surface of the ring, the yarn 20 engaging portion comprising a member extending over the top of the ring, and said yarn engaging portion being pivotally connected to the bearing portion.

7. A spinning ring having an inner frusto-conical bearing surface, and a traveler cooperating therewith having a yarn engaging portion and a bearing portion comprising a block provided with an enlarged bearing surface complemental to and 25 engaging the bearing surface of the ring, the 30 yarn engaging portion comprising a member extending over the top of the ring, and said yarn 35 engaging portion being pivotally connected to the bearing portion.

8. A spinning ring having an inner frusto-conical bearing surface, and a traveler cooperating therewith having a yarn engaging portion and a bearing portion comprising a block provided with an enlarged bearing surface complemental to and 40 engaging the bearing surface of the ring, the 45 yarn engaging portion comprising a curved member extending over the top of the ring and having in-turned ends, and the bearing portion having a 50 hole in which one of the inturned ends of the yarn 55 engaging portion is pivotally positioned.

9. A spinning ring having an inner frusto-conical bearing surface, and a traveler cooperating therewith having a yarn engaging portion and a bearing portion comprising a block provided with an enlarged bearing surface complemental to and 60 engaging the bearing surface of the ring, the 65 yarn engaging portion comprising a curved member extending over the top of the ring and having in-turned ends, and the bearing portion having a 70 hole in which one of the inturned ends of the 75 yarn engaging portion is pivotally positioned, said hole being located to one side of the vertical center of said bearing portion.

10. A spinning ring having an inner frusto-conical bearing surface, and a traveler cooperating therewith having a yarn engaging portion and a bearing portion comprising a block provided with an enlarged bearing surface complemental to and 80 engaging the bearing surface of the ring, the 85 yarn engaging portion comprising a curved member 90 extending over the top of the ring and having in-turned ends, and the bearing portion having a 95 hole in which one of the inturned ends of the 100 yarn engaging portion is pivotally positioned, said hole being located above the horizontal center and to one side of the vertical center of said bearing portion.

11. A spinning ring having an inner frusto-conical bearing surface, and a traveler cooperating therewith having a yarn engaging portion and a bearing portion comprising a block provided with an enlarged bearing surface complemental to and 70 engaging the bearing surface of the ring, the 75 yarn engaging portion comprising a curved member 80

- extending over the top of the ring and having inturned ends, and the bearing portion having a hole in which one of the inturned ends of the yarn engaging portion is fixedly positioned.
- 5 12. A spinning ring, having an inner frusto-conical bearing surface, and a traveler cooperating therewith having a yarn engaging portion and a bearing portion comprising a block provided with an enlarged bearing surface complementary to and 10 engaging the bearing surface of the ring, the yarn engaging portion comprising a curved member extending over the top of the ring and having in-turned ends, and the bearing portion having a hole in which one of the inturned ends of the 15 yarn engaging portion is fixedly positioned, the yarn engaging portion being inclined with respect to the bearing portion in the direction of forward travel.
13. The combination with a spinning ring having an inner bearing surface, and an inwardly extending flange at the lower end of said bearing surface, of an oil reservoir having a chamber disposed below the bearing surface of the ring, and a wick mounted therein having a portion in contact with a portion of said flange.
14. The combination with a spinning ring having an inner bearing surface, and an inwardly extending flange at the lower end of said bearing surface, of an oil reservoir having an annular chamber disposed below the bearing surface of the ring, and an annular wick mounted therein 20
- 25
- 30
- 35
- having a portion in contact with a portion of said flange.
15. The combination with a spinning ring having an inner bearing surface, and an inwardly extending flange at the lower end of said bearing surface, of an oil reservoir having an annular chamber disposed below the bearing surface of the ring, and an annular wick mounted therein 5 having its upper end in contact with the lower face of said flange. 10
16. The combination with a spinning ring having an inner bearing surface, and an inwardly extending flange at the lower end of said bearing surface, of an oil reservoir having an annular chamber disposed below the bearing surface of the ring, and an annular wick mounted therein 15 having its upper end chamfered and in contact with the lower face of said flange.
17. A spinning ring having a bearing surface, and a traveler cooperating therewith having a 20 yarn engaging portion and a bearing portion comprising a block provided with a bearing surface complementary to and engaging the bearing surface of the ring, the bearing portion having a hole in which a part of the yarn engaging portion is mounted, said hole extending entirely through the block and the part of the yarn engaging portion which is mounted therein being shorter than the thickness of the block thereby to provide a 25 pocket in said block adjacent the bearing surface 30 of the ring.

RALPH RAGAN.
